UNITED STATES PATENT OFFICE.

JOSEPH A. GODIN, OF QUEBEC, QUEBEC, CANADA, ASSIGNOR TO UNITED SHOE MACHINERY CORPORATION, OF PATERSON, NEW JERSEY, A CORPORATION OF NEW JERSEY.

FASTENER-INSERTING MACHINE.

Application filed November 12, 1921. Serial No. 514,664.

This invention relates to methods of and machines for inserting fasteners, and is disclosed herein with reference to the inserting of eyelets. The uppers of shoes having 5 visible or blind eyeleting comprise a plurality of layers of material through all of which the lacings are passed but through one of which the eyelets do not extend. In the case of blind eyeleting the eyelets are inserted 10 from the outside of the shoe or other article and are usually clenched between the inside layer and the one next to it, whereas, in the case of invisible eyeleting the eyelets are inserted from the inner side of the article 15 and are clenched between the outside layer and the one next to it. These two kinds of eyeleting have so much in common that both are included within the scope of the invention 20 hereinafter disclosed, and it will therefore be convenient and sufficient to consider both as included within the intent and meaning of expressions such as "invisible eyeleting", thus dispensing with the necessity for specifying both blind and invisible eyeleting 25 whenever the latter is referred to. This is done in this specification merely to avoid repetition and confusion and not with any intent to limit the invention or to imply that blind eyeleting and invisible eyeleting are 30 synonymous.

According to the most approved practice invisible eyeleting is done with a machine having a setting tool the clenching shoulder of which passes through the lacing hole of 35 one of the layers so as to transform and clamp the barrel of the eyelet between that layer and the one next to it. Invisible eyeleting is practiced very extensively and in many of the shoes in which it is used the upper leather is so thick, firm or inelastic as to 40 make it difficult to pass the clenching shoulder through a lacing hole of the small diameter required by the trade. Moreover, as heretofore practiced, the thrust of the ingoing eyelet barrel has been the means relied upon for forcing the upper layer past the 45 clenching shoulder, and this has oftentimes been inadequate.

In view of the conditions hereinbefore explained 50 an object of this invention is to provide an improved method of and improved means for relatively moving the work and a setting tool so as to pass the clenching shoulder of such tool through one layer of the

work to an operative position between two 55 layers prior to and independently of the insertion of the eyelet. The machine herein-after described is designed to utilize a feeding and setting tool separate from the punch that forms the holes, but it is not intended to limit the scope of protection so as to exclude, for example, machines in which the feeding and setting tool is used also to punch the lacing-holes. However the hole may be punched, the operation of locating the 60 clenching shoulder between the layers is preferably timed to occur after the hole has been completely made but before it has been shifted from the punching locality. This timing insures adequate control of the work 65 by the feeding tool during the feeding period.

Accordingly a feature of the invention consists in automatic means including a 70 hammer or presser arranged to act against the work immediately after the leading end of the setting tool has been inserted therein, and to recede from the work as soon as it has forced the layer through which the eyelets are not to pass past the clenching shoulder, 75 to clear the field for the eyelet that is about to be inserted.

Since the work-feeding mechanism of such 80 machines is commonly capable of regulation to vary the length of the feeding steps, another feature of this invention consists in organizing the aforesaid hammer or pressing means and regulatable work-feeding mechanism in such manner that the hammer will 85 partake of regulation of the work-feeding mechanism so as to function always at the locality determined by such regulation.

Another feature of the invention consists in a construction by which the hammer or presser is given an elastic or resilient action 90 to make its operation most effective and to avoid excessive strain on the parts necessary to transmit motion.

In its method aspect the invention provides 95 an improved method for setting invisible eyelets, an important characteristic of which is the moving of the work along the setting tool with the consequent forcing of a layer of the work past the clenching shoulder of the setting tool after the lacing hole is punched but before the work is fed from punching to eyelet-inserting position.

Other features of the invention are illus-

trated by the accompanying drawings and are hereinafter described and claimed.

Referring to the drawings,

Fig. 1 represents a perspective view of a portion of an eyeleting machine embodying a preferred form of the invention;

Fig. 2 is a front elevation thereof in which the work table and an article of work are shown in section;

Fig. 3, on a larger scale, is a view similar to a portion of Fig. 2 excepting that the parts are shown in other positions; and

Fig. 4, from the same point of view as Figs. 2 and 3, shows the inserting tool and the setting tool as completing a clenching operation.

The herein disclosed machine, which is adapted to operate in accordance with the novel method of the present invention and which constitutes an illustrative embodiment of the mechanism of the invention, is of the general type disclosed in United States Letters Patent No. 603,023, granted April 28, 1898, on an application of Seymour Field. It will be convenient for present purposes to confine this description to those parts of the machine that are directly involved in the problem to be considered, since a more complete disclosure of the general organization of the machine may be found in the aforesaid Field patent.

As usual, the machine is provided with a raceway 10 by which the eyelets 11 are supplied to an inserting tool 12. This tool has a central spindle 13 arranged to slide therein and normally pressed upwardly by an enclosed spring (not shown). The inserting tool is carried by a plunger 14 arranged to slide in fixed bearings 15, 15 and provided with a grooved block 16 in which a wrist pin block 17 slides. This block is carried by a wrist pin 18 projecting from a disk 19 on a cam shaft 20. According to the usual well-known operation the inserting tool is caused to rise from the position shown by Figs. 1, 2 and 3, first to pick the leading eyelet from the raceway, then to insert the eyelet into the work and to return to its initial position after it has cooperated with the setting tool to clench the eyelet as shown by Fig. 4.

The setting tool comprises a clenching shoulder 21 and a pilot portion 22 of smaller diameter. This tool is adjustably fixed to a lever 23 so that it may be adjusted endwise to meet the inserting tool more or less closely according to the thickness of the work to be handled. As described in the aforesaid Field patent this lever executes rocking motion such as to carry the setting tool up and down, and also executes a motion of variable amplitude from side to side to feed the work step by step in a straight line.

The setting tool is also provided with an external screw-thread 24 to carry a finger-

nut 25. This nut serves as an abutment to limit the upward movement of the work when the latter is forced on to the setting tool as hereinafter described, and may be adjusted relatively to the clenching shoulder according to the thickness of the upper layer 26 of the work. The work is shown more or less conventionally as comprising only two layers, the layer 27 constituting the eyelet-receiving layer. More often than otherwise the eyelet-receiving element comprises a plurality of layers such as a lining, an eyelet-stay and an inner facing, although, for convenience, the details of its construction are not shown.

The machine also comprises a punch 28 and a punching die 29 for punching holes through all the layers. The diameter of the punch is less than that of the clenching shoulder and about equal to that of the pilot portion 22. As in the aforesaid Field patent the punch is carried by a lever 30 and the die is carried by a laterally movable frame 31 both of which swing in unison about a vertical axis. Furthermore, the lever 30 swings about a horizontal axis to carry the punch toward and from the die. These elements are also connected to the regulatable work-feeding mechanism so as to partake of regulation with the result that they will, in every case, punch the hole at a distance from the setting locality commensurate with the length of the feeding steps.

The feed-regulating mechanism comprises a handle or regulator 32 which is arranged to swing from front to rear over a stationary plate 33. This plate is provided with numerous small holes 34 into any one of which a stop pin 35 may be inserted, a spring (not shown) being provided to urge the regulator toward the rear, and the pin 35 serving to maintain the regulator in any one of a plurality of positions according to the location of the pin. Since this mechanism is essentially the same as that disclosed in the aforesaid patent further description thereof will be unnecessary excepting that it will be convenient to note that a movement of the regulator toward the front of the machine increases the length of the feeding steps and a movement toward the rear decreases their length.

Figs. 1 and 2 show the article of work being held on a stationary work table 36 by a presser-foot 37 which is normally pressed downwardly by a compression spring 38 and periodically lifted by suitable mechanism which is disclosed in the said Field patent. A hole in the work table enables the die 29, the inserting tool 12 and the hammer hereinafter described to operate at the plane of the work-supporting surface. Considering briefly the principal

items in a cycle of operations of the mechanism hereinbefore described, the punch 28 punches a hole through all the layers of the work while the setting tool is in registration with the eyelet-inserting tool, the work being then clamped by the presser-foot. The punch rises immediately to clear the work and then moves to the right, the die 29 moving in unison with it lengthwise of a slot in the work table and the setting tool moving to the right at the same time so as to take the position shown by Fig. 2 where it is in registration with the hole just punched. The setting tool then descends so as to enter the punched hole, whereupon the presser-foot rises to release the work. The setting tool feeds the work by moving from right to left and stops when in alignment with the inserting tool 12. At this point the presser-foot descends to clamp the work. In the meantime the tool 12 has risen to pick an eyelet from the raceway, and is about to insert the eyelet into the work when the setting tool comes to rest as aforesaid. As the barrel of the eyelet enters the element 27 of the work it moves along the pilot portion 22 of the setting tool and encounters the shoulder 21 by which it is spread open and clenched between the elements 26 and 27 as shown by Fig. 4. Incidentally with the aforesaid feeding motion the punch and die return to their original positions so as to be ready to punch the next hole. After clenching the eyelet the setting tool rises and the inserting tool descends, thus completing a cycle of operations.

Machines formerly used for invisible eyeleting have been so arranged that the clenching shoulder of the setting tool has remained above the upper layer of the work until the introduction of the eyelet, the thrust of the entering end of the eyelet barrel being depended upon to move the work upwardly and to force the upper layer of the work past the clenching shoulder of the setting tool. Since it is generally required that the lacing holes be as small as possible and under no circumstances greater than the internal diameter of the clenched eyelets, the clenching shoulder of the tool is larger than the punched lacing holes, and the upper leather is stretched more or less when it is forced past the clenching shoulder. Some grades of leather are thin and elastic enough so that they may be forced past the clenching shoulder by the thrust of the eyelet barrel without much difficulty, but other grades of leather, particularly those which are thick and tough, present a much more difficult condition. Such leathers can be forced past the clenching shoulder only with considerable difficulty, and when the thin entering end of the eyelet barrel is relied upon for this purpose, there is danger of the entering end of the eyelet barrel reaching

and passing the clenching shoulder before the upper leather has been forced completely past the clenching shoulder or even before its upper surface has substantially passed the clenching shoulder. When this happens, the prongs of the eyelet barrel often enter the substance of the upper leather or pass upwardly through the lacing hole and are visible upon the surface of the upper leather or as a circle surrounding the lacing hole, often in a partially clenched condition. Whatever the details may be, if the entering end of the eyelet barrel passes the clenching shoulder before the upper layer of the stock is forced completely past the clenching shoulder, the result is unsatisfactory and often is so bad that the work is ruined.

The mechanism now about to be described is effective to locate the work relatively to the clenching shoulder so that the latter will occupy the relation shown by Fig. 3 prior to and independently of the insertion of the eyelet. The illustrated mechanism for accomplishing this result comprises a hammer 40 formed with a hole 41 only large enough to receive the pilot portion 22 of the setting tool. The mouth of this hole is preferably flared like that of a bell. This hammer is arranged to swing about a pivot member 42 and is operated periodically by a cam 43 carried by the shaft 20. The cam acts upon a lever 44 the fulcrum of which is indicated by 45. A spring 46 normally exerts downward stress on the lever to keep the latter in the position shown by Fig. 2. Motion is transmitted from the lever to the hammer by a link which, as shown, comprises relatively movable sections 47, 48 between which a cushioning spring 49 is interposed. This spring is maintained under initial compression by a sleeve 50 and nut 51, the sleeve being adapted to slide relatively to the member 48 and the nut being effective to vary the degree of initial compression of the spring. A stop 52 is arranged to limit the downward movement of the hammer as caused by the spring 46.

The cam 43 is shaped to cause a sudden upward movement of the lever 44, so sudden that, owing to the inertia of the parts 40 and 48, the spring 49 becomes further compressed by the action of the cam before the hammer has responded fully to such action. The hammer then strikes an upward blow against the work by reason of the reaction of the spring 49, which blow, although not produced directly or positively by the cam, is sharper than it would be if the connection between the lever and the hammer were non-yielding. This permits a less abrupt cam surface than would otherwise be required and relieves the connections from excessively violent impacts, in addition to sharpening the blow against the work.

The cam 43 is timed to produce the afore-

said action of the hammer at that instant when the setting tool has reached the lowest limit of the motion by which it enters the punched hole. The downward movement of 5 the setting tool carries the clenching shoulder approximately to the plane of the upper surface of the layer 26 or slightly above that plane. Then, before the beginning of 10 the feeding movement, the cam 43 causes the hammer to strike the work as aforesaid. Fig. 3 shows the hammer as having struck the blow by which the layer 26 is forced above the clenching shoulder 21, the upward movement of the work being arrested 15 by the abutment 25 which, as hereinbefore stated, will be adjusted relatively to the clenching shoulder according to the thickness of the layer 26. A hole 53 is preferably formed in the hammer so as to be open 20 at its lower end and to communicate with the hole 41, thereby providing an outlet for dirt, chips or other particles that might otherwise accumulate in the hole 41 and prevent the pilot portion 22 from entering. It 25 is thus assured that the pilot portion will protrude below the bottom surface of the work before the eyelet is inserted, which condition is always desirable and usually necessary to avoid crushing the barrel of 30 the eyelet.

It has been stated that the work-feeding mechanism is capable of regulation to vary the length of the feeding steps as in the aforesaid Field patent. Such regulation 35 alters the point at which the holes are punched and produces a corresponding change in the point at which the clenching tool descends to enter the punched hole. Since it is necessary for the hammer 40 to 40 be in registration with the clenching tool to function as shown by Fig. 3 it becomes necessary to shift the hammer in accordance with each feed regulation. This is taken care of by the present invention in such a way that 45 the hammer partakes of feed regulation without requiring any additional or special attention on the part of the operative. Accordingly the hamnier is attached by its pivot member 42 to an adjustable support 50 55. This support is connected to the frame of the machine by screws 55 which extend through horizontal slots 56 formed in said support. Bushings 57 may be placed on the shanks of the screws to furnish greater bearing surface for the support 54. A finger 58 fixed to the support 54 is provided with a stud or antifriction roller 59 which occupies an inclined slot 60 formed in a plate 61. This plate is arranged to slide forward and 60 back on a fixture 62 with which it is connected by a suitable guide such as the dove-tailed formation 63. The forward end of a link 64 is pivotally connected to the slide 61 and the rear end is pivotally connected to 65 the regulating handle 32 by which the am-

plitude of feeding motion is altered as hereinbefore explained and as more fully disclosed in the aforesaid Field patent. The slot 60 is so inclined that when the regulator 32 is moved to increase the length of the 70 feeding steps it will shift the hammer to the right, and when the regulator is moved so as to decrease the length of the feeding steps it will shift the hammer to the left, and thus maintain the hammer in a position such that 75 it will register with the setting tool when these two elements cooperate as shown by Fig. 3. The operating connection between 80 the lever 44 and the hammer is designed to partake of regulating movement without 85 producing any variation in the action of the hammer.

Having thus described my invention, what I claim as new and desire to secure by Letters Patent of the United States is:

1. A machine for inserting fasteners in a plurality of layers of material having a punch, means for operating the punch to cut a hole in the material, a fastener setting tool formed with a clenching shoulder, means for moving the entering end of the setting tool into a hole previously cut by the punch in the material, means for thereafter moving the material along said setting tool thereby forcing a layer of the material past the clenching shoulder of the setting tool to locate said shoulder between the layers, means for thereafter moving the setting tool laterally to feed the material to fastener inserting position, and means for thereafter introducing a fastener and clenching its entering end against the clenching shoulder between the layers.

2. A machine for setting invisible eyelets, comprising a work-feeding tool arranged to enter a lacing-hole in an article of work, said tool having a clenching shoulder, means arranged to move the work so as to force one layer thereof past said shoulder before said tool starts its feeding movement, and means arranged to cooperate with said tool after the feeding movement to insert and set an eyelet in said hole.

3. A machine for setting invisible eyelets, comprising a work-feeding tool having a clenching shoulder, means arranged to punch a lacing-hole through all the layers of the work, means for moving the work along said tool arranged to force said shoulder through one of the layers after such hole has been completely punched but before such hole is removed from the punching locality, and means arranged to cooperate with said tool to insert and clench an eyelet in said hole.

4. A machine for setting invisible eyelets, comprising means for punching a lacing-hole through all the layers of an article of work, eyelet-clenching means having a clenching shoulder formed and arranged to

- go through the punched hole in one layer of said article so as to function between two layers, means arranged to move said article along the axis of said hole so as to locate 5 said clenching shoulder between two of the layers as aforesaid while the punched hole remains at the punching locality, and means arranged to cooperate thereafter with said clenching means to insert and clench an eyelet in said hole. 10
5. A machine for setting invisible eyelets, comprising means for punching a lacing-hole through all the layers of an article of work, eyelet-clenching means having a clenching shoulder formed and arranged to go through the punched hole in one layer of said article so as to function between two layers, means arranged to strike a sharp blow against the work so as to force said 15 layer past said clenching shoulder, and means arranged to cooperate thereafter with said clenching means to insert and clench an eyelet in said hole. 20
6. A machine for setting invisible eyelets, comprising means for punching a lacing-hole through all the layers of an article of work, eyelet-clenching means having a clenching shoulder formed and arranged to go through the punched hole in one layer 25 of said article so as to function between two layers, work-positioning means including a striker normally separate from the work but operative to strike the work so as to force said layer past said clenching shoulder, and means arranged to cooperate thereafter with said clenching means to insert and clench an eyelet in said hole. 30
7. A machine for setting invisible eyelets, comprising clenching means having a clenching shoulder formed and arranged to go into a lacing-hole previously punched through all the layers of an article of work, means formed and arranged to strike an annular area of the work concentric 35 relatively to said shoulder so as to force one of the layers past said shoulder, and means arranged to cooperate thereafter with said clenching means to insert and clench an eyelet in said hole. 40
8. A machine for setting invisible eyelets, comprising a setting tool having a clenching shoulder and a pilot portion protruding therefrom, means for moving said tool so as to insert said pilot portion into a lacing-hole in an article of work, means arranged to move the work lengthwise of said pilot portion simultaneously with the pilot- 45 inserting movement but in the opposite direction so as to force one layer of the article past said clenching shoulder, and means arranged to cooperate thereafter with said tool to insert and clench an eyelet in said hole. 50
9. A machine for setting invisible eyelets, comprising two cooperative members 55 one of which has a clenching shoulder and a pilot portion and the other of which has a recess to receive said pilot portion, said members being movable toward each other to project said pilot portion through and beyond an article of work and to force one layer of the article past said clenching shoulder, means for moving the first-specified member to feed the work after said members have functioned as aforesaid, and 60 means arranged to cooperate thereafter with said shouldered member to insert and clench an eyelet. 65
10. A machine for setting invisible eyelets, comprising a work-feeding tool having a clenching shoulder, mechanism including a hammer arranged to strike the work so as to force one layer thereof past said clenching shoulder, and means arranged to cooperate with said tool to insert and clench an eyelet. 70
11. A machine for setting invisible eyelets, comprising a tool having a clenching shoulder, a hammer and resilient operating mechanism therefor arranged to strike the work so as to force one layer thereof past said shoulder, and means arranged to cooperate thereafter with said tool to insert and clench an eyelet. 75
12. A machine for setting invisible eyelets, comprising regulatable work-feeding mechanism including a feeding tool having a clenching shoulder, work-positioning means including a movable member arranged to move the work so as to force one layer thereof past said shoulder, said member being connected to said feeding mechanism so as to partake of regulating movement of the latter. 80
13. A machine for setting invisible eyelets, comprising regulatable work-feeding mechanism including a feeding tool having a clenching shoulder, a hammer arranged to strike the work so as to force one layer thereof past said shoulder, means arranged to transmit regulating movement from said feeding mechanism to said hammer so as to maintain cooperative relation between the latter and said tool, and mechanism arranged to operate said hammer in all its 85 positions of regulation. 90
14. A machine for setting invisible eyelets, comprising regulatable work-feeding mechanism including a feeding tool having a clenching shoulder, a hammer arranged to strike the work so as to force one layer thereof past said shoulder, an adjustable member arranged to guide said hammer, means arranged to transmit regulating movement from said feeding mechanism to said guiding member so as to maintain cooperative relation between said hammer and said tool, and mechanism for operating said hammer for the purpose stated. 95
15. That improvement in methods of set- 100

ting invisible eyelets which consists in punching a hole through all the layers of an article of work, thereafter moving the work along a setting tool so as to pass the clenching shoulder of such tool through one layer of the work while said hole remains at the punching locality, thereafter feeding the work edge-wise to another locality while maintaining said clenching shoulder in the work, and thereafter inserting and clenching an eyelet in said hole.

16. That improvement in methods of setting invisible eyelets which consists in punching a hole through all the layers of an article of work, thereafter moving the work relatively to a setting tool along the axis of said hole to pass the clenching shoulder of said tool through one layer of the work

while the axis of said hole remains in the same line that it occupied when punched, 20 and thereafter inserting and clenching an eyelet in said hole.

17. That improvement in methods of inserting eyelets in a plurality of layers of material which comprises forming a hole in 25 all the layers of material, thereafter moving the material along a setting tool and thereby forcing one of the layers of the material past the clenching shoulder of the tool, and then feeding the work to eyelet 30 inserting position, inserting an eyelet, and clenching its entering end against the clenching shoulder between the layers.

In testimony whereof I have signed my name to this specification.

JOSEPH A. GODIN.
